UNITED STATES PATENT OFFICE

141,518

DESIGN FOR A SEALING DISK FOR NURSING UNITS, BOTTLES, AND CONTAINERS

Cyril R. Porthouse, Kent, and William B.
McIntosh, Akron, Ohio

Application May 5, 1944, Serial No. 113,489

Term of patent 14 years

(Cl. D58—26)

To all whom it may concern:

Be it known that we, Cyril R. Porthouse and William B. McIntosh, both citizens of the United States, residing in Kent, county of Portage, and State of Ohio, and Akron, county of Summit, and State of Ohio, respectively, have invented a new, original, and ornamental Design for a Sealing Disk for Nursing Units, Bottles, and Containers, of which the following is a specification, reference being had to the accompanying drawing, forming part thereof, in which:

Figure 1 is a top plan view of the sealing disk for nursing units, bottles, and containers, showing our new design;

Figure 2 is a transverse sectional view of the sealing disk taken on line 2—2 of Figure 1;

Figure 3 is a side elevational view of the sealing disk shown in Figure 1; and

Figure 4 is a sectional view of the sealing disk on line 4—4 of Figure 1.

We claim:

The ornamental design for a sealing disk for nursing units, bottles, and containers, as shown.

CYRIL R. PORTHOUSE,
WILLIAM B. MCINTOSH.
